UNITED STATES PATENT OFFICE.

NEWTON COHAN, OF PORTLAND, OREGON.

ADJUSTABLE MAIL CHUTE.

Application filed June 14, 1926. Serial No. 116,058.

This invention relates generally to the delivery of mail, and particularly to a special form of adjustable chute in which mail may be deposited and in which the chute is placed in the air space of a wall.

The main object of this invention is to provide an exceedingly simple and efficient form of mail chute which can be easily placed in a new or old wall without forming any larger openings in the wall than are actually required for the inlet and outlet doors of the chute.

The second object is to so construct the chute that it can be readily adapted to the varying thicknesses of wall.

The third object is to so form the chute itself that it will be flexible enough to allow same to be bent into a shape which will easily pass through the outlet door opening.

The fourth object is to so construct the chute that it can be easily installed by an ordinary mechanic with the aid of ordinary tools.

These, and other objects, will become more apparent from the specification following as illustrated in the accompanying drawing, in which:

Figure 1 is a rear elevation of the device from its outlet side with the outlet door and its casing removed. Figure 2 is a transverse section through the device taken along the line 2-2 in Figure 1. Figure 3 is a horizontal section taken along the line 3-3 in Figure 2. Figure 4 is a horizontal section of one side of the inlet door showing the manner in which it is attached to the chute itself.

Similar numbers of reference refer to the same parts throughout the several views.

Referring in detail to the drawing, in order to illustrate the invention there are shown the usual studdings 10 and wall surfaces 11 and 12, which may be either plaster, composition board or any other material.

The device itself is, for convenience, divided into three parts, namely the outlet box, the connecting chute and the inlet box.

Inlet box.

The inlet box is of somewhat rectangular cross section and is provided with two ends 13, bottom 14 and top members 15 and 16. An inlet door 17 is hinged to the frame 18 by means of the pin 19 and the door itself

is urged to a closed position by means of the spring 20. The frame 18 is held against the inlet box by means of the screws 21 which pass through the nuts 22 which, in turn, are secured to the inner sides of the members 13 by means of the sheet metal clips 23.

Connecting chute.

The connecting chute is divided into two parts, the upper portion consisting of the sides 24, backs 25 and 26 and front 27. The front 27 is preferably integral with the bottom 14 of the inlet box. The bottom 14 is provided with ears 28 at each end which are joined to the members 13 by the rivets 29 which form hinged joints between the members 13 and 28. The upper end 30 of the member 26 is curled inwardly and acts as a stop for the turned edge 31 of the member 16. On the lower end of the back 25 is formed a hinge 32 to which is attached the back 33 of the lower portion of the connecting chute, whose sides 34 are on the outside of the sides 24, and whose front 35 is on the outside of the front 27. The upper edge 36 of the front 35 overlaps the lower edge 37 of the member 27.

Outlet box.

The outlet box is joined to the member 35 by means of the hinge 38 and consists of the two side members 39, the back 40 and top 41 as well as a bottom 42. An angular lip 43 which is hinged between the members 39 by means of the rivets 44 which pass through the lugs 45, forms a close fit with the member 33 regardless of the angular relation between the connecting chute and the outlet box. An outlet door 46 is attached to the frame 47 by means of the hinges 48, and the door itself may be held in a closed position by means of a latch 49 which can be operated by the knob 50. Nails 51 are employed to secure the chute to the studding 10 when in its correct position.

Installation of the device is as follows: An opening is cut through the inner wall 11 just large enough to receive the outlet box, which has the largest cross section of any of the members in the device. A second opening is cut through the outer wall 12 just large enough to receive the inlet box, and of course, sufficiently above the first mentioned hole to receive both ends of the device at the same time.

In finished walls the device is bent into

the form indicated in dotted lines in Figure 2, which permits it to slip into place without increasing the wall openings greater than the amount required for the introduction of the members. The chute is straightened out when in position within the wall, as shown in full lines in Figure 2. Nails 51 are now driven through the side members 39 into the studding 10, which is sufficient to hold the device in position. The frames 18 and 47 are now fastened in position over their respective openings and the device is ready for use.

For new work where the device is installed before the house is plastered, or the inner side of the studdings covered with any other material, it is not necessary to curve the chute as suggested. In fact, the hinge 32 can be eliminated entirely, and the entire 20 connecting chute may be made one solid piece.

It will be observed that, regardless of the thickness of the studdings 10 which affects the depth of the air space, this mail chute 25 can be adapted to suit the particular conditions present without in any way altering the construction of the device or performing any operation other than moving the inlet and the outlet boxes into the proper lateral 30 position.

It will also be understood that the particular type of hinges employed and their exact location is immaterial. For instance, the hinge 38 could also be placed on the opposite side of the chute and the lip 43 incorporated in the member 33, and similar other variations in details could be employed without departing from the spirit of this invention.

I am aware that mail chutes have long 40 been constructed in the past; I have therefore directed my claims to a special form of mail chute adapted to be adjusted between its foremost and rearmost faces for the pur-

pose of accommodating itself to various 45 thicknesses of walls especially adapted for installation in existing walls without marring the walls or the formation of greater openings therein than are actually occupied by the inlet and outlet boxes. It is therefore 50 not my intention to limit myself to the precise form illustrated in the drawing, but I do intend to cover all such forms and modifications of the device as fall fairly within the appended claims.

I claim:

1. An adjustable mail chute having an inlet duct; an outlet duct below said inlet duct; and a connecting chute flexibly joining said inlet and outlet ducts adapted to permit changes in distance between the foremost edge of the inlet duct and the rearmost edge of the outlet duct, said flexible chute being bendable to permit same to pass upwardly through the lower wall opening and then to project through an upper opening of the completed wall.

2. An adjustable mail chute for hollow walls having an inlet box provided with a closure at one end; a bendable chute connected to the opposite end of said inlet box and adapted to extend downwardly in a wall space; an outlet box hinged to the lower end of said chute; and closure means for the rearward end of said outlet box.

3. An adjustable mail chute adapted to be placed in the air space of a wall, having an upper inlet duct; a closure for said inlet duct on the outer side of the wall; an outlet duct adapted to pass through the inner side of the wall below said inlet duct; a closure for said outlet duct; a connecting duct hinged at its mid portion to permit the bending of said chute and hinged at its upper end to said inlet duct and at its lower end to said outlet duct.

NEWTON COHAN.
